(57) **CLAIM**

An ornamental design for an artificial eyelash extension applicator, as shown and described.

DESCRIPTION

FIG. 1 is an illustration of a front perspective view of an artificial eyelash extension applicator;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top view thereof;

FIG. 7 is a bottom view thereof; and,

FIG. 8 is a bottom perspective view thereof.

The broken lines in the drawings depict portions of the artificial eyelash extension applicator that form no part of the claimed design.
